Primary Examiner — Ricky Pham(74) *Attorney, Agent, or Firm* — Barry E. Kaplan(57) **CLAIM**

The ornamental design for a poultry rack, as shown and described.

DESCRIPTION

FIG. 1 is a perspective view of the poultry rack;
 FIG. 2 is a side elevation view of one side of the poultry
 rack;
 FIG. 3 is a side elevation view of the opposite side of the
 poultry rack;

FIG. 4 is a first end elevation view of the poultry rack;
 FIG. 5 is an opposite end elevation view of the poultry rack;
 FIG. 6 is a top plan view of the poultry rack; and,
 FIG. 7 is a bottom plan view of the poultry rack.

Shading shown in the figures is for illustrative purposes to
 show surface contours in the drawings only and forms no
 part of the invention.
